UNITED STATES PATENT OFFICE.

ARTHUR H. FOWLER, OF NEWARK, OHIO.

POR TABLE BASE-BURNING BOILER.

SPECIFICATION forming part of Letters Patent No. 271,621, dated February 6, 1883.

Application filed March 1, 1882. (No model.)

To all whom it may concern:

Be it known that I, ARTHUR H. FOWLER, of Newark, in the county of Licking and State of Ohio, have invented a new and useful Improvement in Portable Base-Burning Boilers; and I do hereby declare that the following is a full, clear, and exact description of the same.

My invention relates to base-burning boilers of that class which are constructed of iron without any brick-work.

The invention consists in certain details of construction, the object of which is to simplify the boiler and to increase its capacity and durability. These details are hereinafter fully described, and specifically indicated in the claim.

In the accompanying drawings, Figure 1 represents a vertical central section of my improved boiler. Fig. 2 is a transverse section on line $\alpha\alpha$ of Fig. 1. Figs. 3 and 4 represent modifications of the boiler.

In these drawings the lower and main part of the boiler is composed of a double wall, aa , which wall incloses an annular water-space and surrounds the fire-chamber. This annular boiler is formed, as shown in Fig. 1, of plain annular walls, with annular heads substantially channel-iron form in cross-section, these heads being inserted between the walls aa and bolted or riveted thereto both at the upper and lower ends. This annular part of the boiler, cylindrical in form, rests upon a cast-iron annular base, also shown in Fig. 1. The base is cast with an inner flange, b , about which the cylindrical boiler rests, the upper edge of which supports the grate. Within this base is a nearly-annular smoke-chamber, interrupted only by the space excluded by transverse walls to form the ash-door, and opposite the ash-door is represented an exit for the smoke. The annular chamber is provided with smoke-flues $A A$, which pass through the heads and open above into the annular space connected with the interior fire-space and below into the annular smoke-chamber in the base.

The upper and interior part of the boiler is composed of a separate section, (marked B .) This consists of an upper cylindrical part, c , and a lower conical part, d , throughout the whole extent of which is a cylindrical magazine for the coal. The walls of the section B ,

both within and without, are of boiler-iron, securely bolted or riveted together, or of equivalent material, and are supported upon three or more lugs, d^2 . The lower part of the conical boiler is formed by a special constriction, consisting of a ring, K , which is U-shaped in cross-section, placed within and bolted to the edges of the conical-boiler section, in the manner shown in Fig. 1. This U-shaped ring may be formed of cast-steel or any other suitable material capable of resisting the action of the greater heat to which it is exposed. The construction also brings the riveted joints at a distance from the hottest of the fire.

About the upper part of the conical portion of the boiler is a smoke-belt, which includes the upper end of the annular section, and opens into the interior of the fire-chamber by an annular space between the conical part of the boiler and the upper end of the lower section. This is covered in part by solid sheet metal, riveted to the cylindrical part of the upper section and resting upon the outer edge of the upper end of the cylindrical part, thus aiding in supporting the upper part upon the lower. In part this belt is closed by covers d' , provided with handles, and removable at pleasure for the purpose of cleaning the inside of the boiler or the smoke-tubes. The upper section of the boiler is connected to the lower by means of pipes E , as shown in Fig. 1.

The fire-door is formed of a casting of proper size, and the walls are riveted thereto. The ash-door (shown at g) is through the base, being provided with side walls, which close the ends of the nearly-annular smoke-space in the base, the ash-door forming an interruption of this space. The grate is made to rest upon the flanges $b b$ of the base.

When soft coal is to be burned, I provide the magazine with a sleeve, H , having flange h , adapted to rest upon the rim of the magazine. This is made a trifle smaller than the magazine, so as to leave space of about one-fourth of an inch between its outer walls and the inner walls of the magazine. The sleeve is made slightly tapering from the lower end upward to permit the coal to fall freely, and provided with holes about half-inch in diameter to allow the gases to escape from the sleeve into the annular space, whence they pass downward.

into the fire. It will be understood that the coal is held within a tapering sleeve. The flange is to fit tight to the flange of the magazine, and the sleeve is to be provided with a suitable cover. In Fig. 3 I have shown an addition to this modification of the boiler, in which the lower annular part is provided with two sets of tubes, the inner being the downward tubes and the outer the up tubes. The inner, which are marked *n*, conduct the products of combustion into the annular smoke-space in the base, whence they pass through the outer tubes, *m*, into the smoke-belt, heretofore described, at the upper end of the annular section. In this modification, however, a wall, *o*, separates the inner side of the smoke-belt from the interior of the fire-chamber, and this wall *o* separates the inner and outer rows of tubes. The smoke-outlet in this case is represented at *M*, and is from the smoke-belt. The pipe-connections are the same. The tubes in this form, as in that first described, extend throughout the annular lower section, excepting in that part occupied by the fire and ash doors.

The construction of the conical section protects the magazine from the fire, leaving ample space for the escape of the products of combustion, which by the smoke-tubes are passed over surfaces in contact with the water, and

give up nearly all their heat before reaching the atmosphere.

F is a shell of sheet metal placed in the conical water-jacket, resting on lugs in the walls of the same. It is intended to assist the circulation of the water in the chamber by separating the cooler water from that exposed to the heat from the smoke-space, and thus cause a constant circulation.

Having thus described my invention, what I claim is—

In a boiler, the combination of an upper section composed of a fuel-magazine, a steam-space, and a tapering water-space surrounding the magazine, an annular water-leg having smoke-tubes and forming the lower section, a smoke-space between the two sections, having removable lids or covers, for the purpose set forth, and the circulating-pipes connecting the inner and outer water-spaces, all substantially as described.

In testimony whereof I have signed my name to this specification in the presence of two subscribing witnesses.

ARTHUR H. FOWLER.
